UNITED STATES PATENT OFFICE.

RICHARD JOHN CRACKNELL, OF STREATHAM, ENGLAND.

ROTARY PUMP OR COMPRESSOR.

1,359,792.

Specification of Letters Patent. Patented Nov. 23, 1920.

Application filed May 10, 1920. Serial No. 380,273.

To all whom it may concern:

Be it known that I, RICHARD JOHN CRACKNELL, a subject of the King of England, and residing at Streatham, Surrey, in England, have invented certain new and useful Improvements in Rotary Pumps or Compressors, of which the following is a specification.

This invention relates to rotary pumps or compressors of the type in which an inner rotary member is mounted eccentrically within an outer rotary member and both members are adapted to rotate at the same angular velocity within a fixed outer casing. The object of this invention is to simplify the construction of such apparatus, to provide a machine which is fluid tight while absorbing less power than those hitherto proposed, and to provide improved means for causing the simultaneous rotation of the two rotary members in the same direction and at the same angular velocity.

According to this invention means are provided for maintaining a seal of liquid between relatively moving parts of the apparatus to lubricate all wearing parts and prevent leakage of compressed fluid past such relatively moving parts. Further, this liquid may serve the additional purpose of carrying away the heat of compression when the apparatus is used for compressing some fluid. The coupling mechanism connecting the two rotary members is mounted within the outer rotary member and is disposed in a chamber formed between one end of the latter and the adjacent end of the inner rotary member. The sealing and lubricating liquid circulates from the lower part of the fixed outer casing through suitable inlets communicating through conduits with the bearings of the rotary members, with the chamber containing the coupling mechanism, and with all portions of the rotating members which are in contact and between which relative movement occurs.

The inner rotary member carries one or more sliding vanes and a supply of lubricant is maintained over the inner end of the vanes which thus serves both to lubricate the vanes and to prevent leakage of the fluid to be compressed past any of their edges in the manner hereinafter described.

The invention is particularly applicable to vacuum pumps or for compressing air or other gas to a moderate pressure as for in-

stance for refrigerating purposes and one form of apparatus embodying the invention suitable for these purposes is illustrated by way of example in the accompanying drawings, in which—

Figure 1 is a central longitudinal section.

Fig. 2 is a cross section of the rotary members on the line 2—2 of Fig. 1.

Figs. 3, 4 and 5 are diagrammatic views showing the relative positions of the coupling mechanism and the outer rotary member at various stages in the revolution of the latter.

Figs. 6 and 7 are cross sections of the rotary members showing a modified construction of apparatus according to this invention with two radial slots and vanes instead of one.

With reference first to Figs. 1 and 2, the apparatus comprises a hollow cylinder or drum A forming the inner rotary member mounted in a gas tight manner upon a shaft C which is hollow for a portion of its length, this shaft being carried in bearings C¹ and C² secured to the inner walls of a fixed outer casing B. The open end of the hollow shaft engages a socket or sleeve C⁶ secured to the fixed casing and constituting the inlet passage for the fluid to be compressed, ports C⁸ in the wall of the hollow shaft establishing communication with the interior of the drum. The solid end of the shaft extends outwardly through an annular chamber B¹ and passes through a stuffing box on the fixed outer casing. Inclosing the drum is a cylinder D forming the outer rotary member, this cylinder being mounted on independently adjustable bearings D¹ and D² capable of being locked to the fixed casing in their correct position eccentric to those of the drum. The precise form of these bearings may vary provided they can be adjusted independently of those of the drum and locked to the fixed outer casing by suitable bolts or the like which have clearance in their holes, when the desired adjustment has been automatically obtained by allowing the inner periphery of the cylinder to rest upon the outer periphery of the drum. The amount of eccentricity and the relative diameters of the drum and cylinder are then such that there is always contact between the outer periphery of the drum and the inner periphery of the cylinder at one point throughout each revolu-

tion. The ends of the drum are recessed so as to form around the hollow shaft an annular chamber E and E¹ between each end of the drum and the adjacent inner end wall 5 of the cylinder, so that only the outer rims or edges A¹ A² of the drum are in sliding contact with the end walls of the cylinder.

Formed in the drum and extending from end to end thereof is a radial slot F (Fig. 2) 10 provided with inwardly projecting side walls F¹ connected by a base F² and constituting a passage connecting the chambers E, E¹ at each end of the drum. As the sides and base or inner end wall of the slot are 15 inclosed, the radial chamber thus formed does not communicate with the interior of the drum. In this slot and adapted to slide radially therein is a vane G which extends the whole length of the drum and across 20 the crescent-shaped space between the drum A and the cylinder D, this vane reciprocating in the slot in the usual manner as the drum and cylindrical casing D are rotated, being held in contact with the inner periphery of the cylinder at all times by centrifugal force with or without the addition of one or more springs.

A suction port H is formed in the drum on one side of the vane through which the 30 fluid to be compressed is drawn from the interior of the drum into the crescent-shaped space between the circumferential periphery of the drum and the inner wall of the cylinder D, and on the opposite side 35 of the vane to the suction port in the wall of the cylindrical casing D is formed an outlet J for the compressed fluid. The outlet port is conveniently provided with a known form of light spring valve J¹ with a 40 suitable guide or cover J² to retain it upon its seat against the centrifugal force until the pressure of the fluid in the crescent-shaped space causes the valve J¹ to open. Both the drum A and the cylindrical casing 45 D which rotates with it are inclosed within the outer fluid-tight casing B and this is provided with an outlet port B³ through which the compressed fluid is delivered.

To insure a fluid-tight joint being maintained along the bearings of the cylinder and between relatively movable parts of the apparatus, lubricant is circulated from the base of the fixed outer casing by a pump P through the pipe K into the annular chamber B¹ thence through the passages K¹ and K² into the interior of the adjustable bearing D¹, holes K³ being provided to lubricate this bearing. The lubricant is thus supplied to the chamber E¹ formed between the adjacent end of the drum A and cylinder D and thus to the radial slot F in which the vane G is disposed, the annular chamber E, the interior of the adjustable bearing D² and by the conduit K⁴ to the sleeve C⁶. The 60 lubricant delivered into the chambers E, E¹ 65

at the ends of the drum, is thrown outward by centrifugal force to form an annular seal of liquid at each end of the drum and along the inner end of the vane, suitable overflow apertures such as D⁴ through 70 the bearing D² determining the depth of the liquid seal so formed. Any leakage that may take place past the sides of the vane G or past the ends of the drum, will be leakage of the lubricant inward into the crescent-shaped space, as this lubricant is under the delivery pressure in addition to the pressure due to centrifugal force. By this means therefore leakage of the fluid to be compressed past these relatively moving 80 members will be entirely prevented and at the same time a bath of lubricant will be provided.

The quantity of liquid delivered into the annular chamber B' surrounding the driving shaft being greater than can escape by leakage, the surplus will overflow through the passages D⁴ provided in the bearing D² and is thus discharged into a fixed outer casing B, the lower part of which forms a 90 reservoir for the lubricant which is thus available for repeated use. A continuous circulation of lubricant is maintained, as for instance by means of the small pump P which draws the lubricant from the reservoir in the base of the fixed casing and delivers it as above described. The lubricant which leaks past the sides of the vane G and ends of the drum forms, by centrifugal force, a thin film on the inner circumference 100 of the outer cylinder and thus serves to lubricate the outer end of the vane which bears on the inner periphery of the cylinder, thus insuring the free reciprocation of the vane G within its slot F, and at the same 105 time acting as a seal to prevent the escape of fluid to be compressed past the outer end of the vane or between those parts of the drum and cylinder which are in contact. Any lubricant which thus leaks into the crescent-shaped space is finally discharged with the compressed fluid, into the outer casing, suitable baffles such as B⁴ being provided in the upper part of this casing to prevent its delivery with the compressed fluid. The 110 lubricant in the annular reservoir or chamber B' surrounding the driving shaft C also forms a seal to prevent the escape of compressed fluid or the leakage of air inward when the apparatus is used as a vacuum 115 pump.

The coupling mechanism whereby the cylindrical casing D is caused to rotate simultaneously with the drum A and at the same angular velocity may vary, but is disposed 125 in the chamber formed between one end of the drum A and the adjacent inner end of its cylindrical casing D. Preferably this coupling member is at the end of the apparatus remote from the driving shaft C 130

and in the construction shown is disposed in the chamber E. In the present instance projecting members, for example steel keys M formed on the outer end wall of the drum 5 A and similar members N formed on the inner end wall D³ of the casing D, respectively engage guides or slots M¹, N¹ provided in the opposite faces of an annular disk O which is free to float about the hollow portion 10 of the shaft C. The guides M¹ on one face of the disk are at right angles to those N¹ on the other face, so that as the drum A is rotated by means of the driving shaft the projections M thereon move in their respective guides M¹ and rotate the casing D, whose projecting members N similarly move 15 in their guides N¹ but in a direction at right angles to those on the drum, at the same angular velocity.

20 The operation of the floating annular disk O is further illustrated in the diagrams forming Figs. 3-5. In these diagrams the axis of rotation of the drum A is shown at A A and that of the outer rotary member D at D D. The drum A is omitted but the keys M which project from its end wall are shown. The grooves N¹ engaged by the keys N secured to the end wall D³ of the outer rotary member are formed on the under side of the annular disk O.

30 When the drum A and the keys M rotate about its center A A through 45° into the position shown in Fig. 4, the keys N are also moved through a similar angle and the disk O, coupling these members A and D slides on the keys M, N into the position shown in Fig. 4. Further rotation through another 45° brings the disk into the position shown in Fig. 5.

40 From the above it will be seen that though not mounted about the same axis, the keys on the two rotary members by engaging their respective grooves in the disk O effect the rotation of the drum and outer rotary member at the same angular velocity.

45 The chamber E in which the coupling mechanism is disposed contains sufficient lubricant for all the moving parts of this mechanism to be constantly immersed, a bath of lubricant being thus provided.

50 In operation, the fluid to be compressed is drawn through the hollow shaft and openings C³ into the interior of the drum A and passing through the suction aperture H behind the radial vane G is compressed in the crescent-shaped space as the drum A and casing D rotate. When the pressure within the crescent-shaped space exceeds that within the fixed casing B, the valve J¹ controlling the outlet port J will open, whereupon the fluid thus compressed is discharged into the fixed casing whence it is delivered to the desired point, the baffles B⁴ separating any lubricant which may have been delivered 55 with the charge. The valve J¹ controlling

the discharge port J is provided for the purpose of preventing the fluid within the outer casing reentering the crescent-shaped space.

The heat of compression is taken up by the lubricant, which may in turn be cooled 70 by being passed through tubes immersed in cold water or in any other known manner after it has been drawn from the fixed casing by the pump and before it is returned for repeated use.

75 Where such an arrangement is provided the lubricant thus serves the three purposes of lubricating all wearing parts, sealing all parts where leakage of compressed fluid might take place, and carrying away the 80 heat of compression.

The apparatus is especially suited for compressing gases which liquefy at low pressures such as ether, ethyl chlorid, or the like for refrigerating purposes, in which 85 case the heat of compression may be removed in the known manner by allowing the fluid to be compressed to enter the apparatus in a saturated or super-saturated condition.

90 Figs. 6 and 7 illustrate a modified construction of apparatus also according to this invention having two radial slots or compartments and vanes sliding therein instead of one. In this construction a port H¹ is formed through the rear side wall of each of the radial slots or compartments F³ instead of being formed through the periphery of the drum A and the vanes G¹ are provided with ports G² so formed that when the vanes are at right angles to a line passing through 95 the centers of the inner and outer rotary members the port in one vane is about to open while the port in the other vane is about to close. This is the position shown in Fig. 7. The direction of rotation is 100 shown by the arrow and in Fig. 6 the fluid in the space to the left of the lower vane G² is being compressed while low pressure fluid is passing from the interior of the drum through the ports H¹ and G² into the crescent-shaped space, the port G² in this position being full open. The volume of fluid drawn in during each revolution is proportional to twice the area of that part of the crescent-shaped space (which forms what 110 may be termed a truncated crescent) below the vanes G when they are in the position shown in Fig. 7.

115 Delivery ports J³ are provided through the cylinder D in front of the vanes G¹ in 120 the direction of rotation that is to say on the opposite sides of the vanes to the ports G². These delivery ports are provided with suitable valves J⁴ similar to the valves J¹ previously described with reference to 125 Fig. 2.

130 In this construction the keys M shown in Fig. 2 are dispensed with the ends of the vanes G¹ engaging with the slots M¹ in the annular disk O but guides or slots N² at

right angles to those engaged by the ends of the vanes G^1 are formed on the opposite face of the disk O and are engaged by projecting keys N^3 on the inner end wall of the cylinder D .

As the inner rotary member A is rotated by means of its driving shaft the ends of the vanes G^1 will carry with them the annular disk O which in turn by engaging the projecting keys N^3 on the end wall of the outer rotary member D effects the rotation of the latter at the same angular velocity as the drum. Similarly when a single vane is used as in the construction illustrated in Fig. 1 if the radial slot or compartment for the vane is in line with one of the keys M the end of the vane may be used to engage the slot in the annular disk O instead of the key, only one key M then being employed on the side opposite to the vane.

Instead of circulating the lubricant by means of a pump the circulation may be produced automatically by the difference of pressure which results when the compressor is in operation. This can be done for instance by providing a small hole C^4 (Fig. 1) through the hollow shaft and omitting the overflow opening D^4 through the bearing D^2 . The result of this is that the pressure in the annular chamber E , radial slot or slots, chamber E^1 and annular chamber B^1 will be reduced as communication is established between these spaces and the suction side of the compressor through the small opening C^4 . At the same time the delivery pressure acts on the surface of the lubricant in the base of the fixed casing B and therefore flows up the pipe K into the annular chamber B^1 and thence as previously described into the annular chambers E^1 and E until it reaches the opening C^4 when a small quantity of the lubricant will pass through this opening into the suction side of the compressor at each revolution, being finally discharged with the compressed fluid into the fixed outer casing B where it may be separated from the compressed fluid by the baffles B^4 the compressed fluid passing out by the opening B^3 and the lubricant falling down to the lower part of the casing for further use. A continuous circulation of the lubricant is thus automatically set up so long as the compressor is in operation without the use of a separate pump. In such a case the lubricant may be cooled in any known manner.

It will be appreciated that though described as a compressor for fluids the apparatus is equally applicable to rotary pumps and compressors generally and that the details of construction of the apparatus as a whole or of the coupling mechanism may be modified without departing from this invention. In the following claims the

term pump is used throughout but it is to be understood as including a compressor.

What I claim as my invention and desire to secure by Letters Patent is:—

1. In a rotary pump the combination of an outer rotary member, an inner rotary member mounted eccentrically therein and adapted to rotate therewith at the same angular velocity, a radial vane extending across the space between the inner and outer rotary members, a fixed outer casing inclosing both rotary members, and means for maintaining a seal of liquid in the joints between the relatively moving parts of the apparatus which inclose the chamber in which the air is compressed whereby these parts are lubricated and escape of compressed fluid is prevented. 70 75 80

2. In a rotary pump the combination of an outer rotary member having a discharge port therein, an inner rotary member eccentrically mounted within the outer member such inner member having a suction port and being adapted to rotate with the outer rotary member at the same angular velocity, a chamber at each end of the inner rotary member, a radial compartment formed in the circumferential wall of the inner rotary member said compartment connecting the chambers, a vane mounted to slide in the radial compartment, means for supplying lubricant under pressure to the chambers and to the compartment for the purpose described and a fixed outer casing inclosing both rotary members. 85 90 95

3. In a rotary pump the combination of an outer rotary member having a discharge port therein, an inner rotary member eccentrically mounted within the outer member such inner member having a suction port and being adapted to rotate with the outer rotary member at the same angular velocity, a chamber at each end of the inner rotary member, a radial compartment formed in the circumferential wall of the inner rotary member said compartment connecting the chambers, a vane mounted to slide in the radial compartment, means for supplying lubricant under pressure to the chambers and to the compartment for the purpose described, a fixed outer casing inclosing both rotary members and means for adjusting the position of the outer rotary member relatively to the inner rotary member. 100 105 110 115

4. In a rotary pump the combination of an outer rotary member, an inner rotary member mounted eccentrically therein, mechanism coupling the inner and outer rotary members so that they rotate at the same angular velocity such coupling mechanism comprising an annular disk having guides on its opposite faces, the guides on one face being at right angles to those on the other, said disk being mounted between adjacent ends of the inner and outer rotary mem- 120 125

bers, projections on said adjacent ends so engaging the guides as to reciprocate the disk relatively to the axes of the rotary members, a radial vane extending across the space between the inner and outer rotary members and a fixed outer casing inclosing both rotary members.

5. In a rotary pump the combination of an outer rotary member, an inner rotary member mounted eccentrically therein, mechanism coupling the inner and outer rotary members so that they rotate at the same angular velocity such coupling mechanism comprising an annular disk having guides on its opposite faces, the guides on one face being at right angles to those on the other, said disk being mounted between adjacent ends of the inner and outer rotary members, projections on said adjacent ends so engaging the guides as to reciprocate the disk relatively to the axes of the rotary members, a radial vane extending across the space between the inner and outer rotary members, a fixed outer casing inclosing both rotary members; and means for maintaining a liquid seal between relatively moving parts of the apparatus for the purpose described.

6. In a rotary pump the combination of an outer rotary member, an inner rotary member mounted eccentrically therein, mechanism coupling the inner and outer rotary members so that they rotate at the same angular velocity such coupling mechanism comprising an annular disk having guides on its opposite faces, the guides on one face being at right angles to those on the other, said disk being mounted between adjacent ends of the inner and outer rotary members, projections on said adjacent ends so engaging the guides as to reciprocate the disk relatively to the axes of the rotary members, a radial vane extending across the space between the inner and outer rotary members, a fixed outer casing inclosing both rotary members, means for maintaining a liquid seal between relatively moving parts of the apparatus for the purpose described and means for adjusting the position of the outer rotary member relatively to the inner rotary member.

7. In a rotary pump the combination of an outer rotary member, an inner rotary member mounted eccentrically therein and adapted to rotate therewith at the same angular velocity, said inner rotary member having two diametrically opposed radial compartments, vanes slidably mounted in said compartments controlling suction ports formed in the compartments and so disposed that when the vanes are at right angles to a line passing through the centers of the inner and outer rotary members one suction port is about to open and the other about to close, outlet valves in the outer rotary member on the opposite sides of the

vanes to the suction ports, a chamber at each end of the inner rotary member such chambers communicating with each other by means of the radial compartments and a fixed outer casing inclosing the rotary members.

8. In a rotary pump the combination of an outer rotary member, an inner rotary member mounted eccentrically therein and adapted to rotate therewith at the same angular velocity, said inner rotary member having two diametrically opposed radial compartments, vanes slidably mounted in said compartments controlling suction ports formed in the compartments and so disposed that when the vanes are at right angles to a line passing through the centers of the inner and outer rotary members one suction port is about to open and the other about to close, outlet valves in the outer rotary member on the opposite sides of the vanes to the suction ports, a chamber at each end of the inner rotary member such chambers communicating with each other by means of the radial compartments, a fixed outer casing inclosing the rotary members, and means for supplying lubricant under pressure to the chambers and compartments for the purpose described.

9. In a rotary pump the combination of an outer rotary member, an inner rotary member mounted eccentrically therein and adapted to rotate therewith at the same angular velocity said inner rotary member having two diametrically opposed radial compartments, slideable vanes mounted in said compartments controlling suction ports formed therein, outlet valves in the outer rotary member on the opposite sides of the vanes to the suction ports, a hollow shaft communicating with the interior of the inner rotary member and a fixed outer casing inclosing the rotary members the whole arrangement being such that the volume of fluid drawn in during each revolution is proportional to twice the area of the truncated crescent-shaped space between the two vanes when they are at right angles to a line passing through the centers of the inner and outer rotary members.

10. In a rotary pump the combination of an outer rotary member, an inner rotary member mounted eccentrically therein, an annular disk between adjacent ends of the rotary members, means for driving one of said rotary members, and slideable engaging means between the disk and the adjacent ends of the rotary members whereby said members are caused to rotate at the same angular velocity substantially as set forth.

11. In a rotary pump the combination of an outer rotary member, an inner rotary member mounted eccentrically therein and having diametrically opposed radial compartments, vanes mounted in said compartments,

115

120

125

130

ments, an annular disk between adjacent ends of the rotary members, guides in said disk engaging the ends of the vanes, other guides in said disk at right angles to the vane-engaging guides, and projections on the adjacent wall of the outer rotary member making sliding engagement with said

other guides for the purpose described and means for driving one of the rotary members.

In testimony whereof I have signed my name to this specification.

RICHARD JOHN CRACKNELL.
